CHIME OR BELL INSTRUMENT VOLUME CONTROL FOR USE WITH AN ORGAN OR SIMILAR ARTICLE

Jacob T. Kunz, Collegeville, Pa., assignor to Schulmerich Electronics, Inc., Sellersville, Pa., a corporation of Pennsylvania

Application May 15, 1956, Serial No. 41,506

Term of patent 14 years

(Cl. D26—13)

Fig. 2.

Fig. 1 is a top perspective view of a chime or bell instrument volume control for use with an organ or similar article, showing my new design;

Fig. 2 is an enlarged bottom perspective view; The fragmentary dotted line showing of an organ casing is for illustrative purposes only.

I claim:

The ornamental design for a chime or bell instrument volume control for use with an organ or similar article, substantially as shown and described.
